UNITED STATES PATENT OFFICE.

JOHN JENKINS, OF STAVELY, ALBERTA, CANADA.

DOOR FOR GRAIN CARS.

Application filed January 15, 1926. Serial No. 81,503.

My invention relates to improvements in doors for grain cars in which it is sought to provide an economical and reusable door, which can be opened for delivery of the grain by simple means.

My device is illustrated in the accompanying drawings in which:—

Fig. 1, is an elevation of the lower portion of a doorway with the device in position.

Fig. 2, is the plan of a doorway with the device in place.

Fig. 3, is a section along the line A.B.

Fig. 4, is a perspective view of the locking bolt.

Fig. 5, is a fragmentary perspective view of the device in place.

Similar numerals refer to similar parts throughout the several views. The device consists of a cast member supporting a bolt, formed to detachably engage with one jamb of a doorway, which cast member supports one end of a plank transverse the door opening, the other end of the plank being supported by the door jamb opposite the cast member. The plank 2, is held in position by the outward thrust of the grain in the conveyance.

The casting 1, in the preferred embodiment of my invention is of angular cross section, having formed in the internal angle, and integrally with the main casting, a sleeve 3. The said sleeve has frontal, external orifices or ports for the purpose hereinafter mentioned. Slidably engaged in the said sleeve is the locking bolt 6, having recessed notches in same at 7 and 8 suitably disposed to bear a definite relationship to the ports 4 and 5 in the sleeve 3. The lower portion of the bolt member 6, is formed to circular cross section to enter into a socket 10 cut in the sill of the doorway. The face of the bolt member 6, opposite to the notches 7 and 8, contains a groove 11, terminated short of the upper and lower ends of the bolt. The threaded screw 12 passes through the wall of the main casting into the groove 11, referred to, and prevents the bolt member from dropping out of its sleeve when the device is not in use.

The main casting 1, is finished at its upper end into a lug 13, extended as shown to provide an engagement with a socket 14, cut in the interior wall of the conveyance, adjacent to the doorway. This forms a simple pivotal bearing for the rotation of

the main casting in a plane parallel to the face of the door jamb. It is contemplated that the casting may be detachably secured to the door jamb when necessary with a short chain 15, hooked over a suitable fastening on the door jamb.

The main casting 1, has also a vertical rib 16, on the face presented to the interior of the conveyance, to prevent travel endways of the plank 2. The opposite end of plank 2 to that engaged with the casting passes beyond the door opening and bears on the interior side of that door jamb. It is held at that end by the cleat 17 and further by the angle piece 18, bolted to the plank.

The device in use is erected by engaging the casting 1, with a prepared door jamb, the lug 13 being entered into the socket 14, and the bolt member 6 being thrust down into the sill socket 10. The plank 2 is then placed in position and is held there by the outward thrust of the grain deposited behind same. To discharge the grain a crow bar is inserted into ports 5 and 4, and by engagement with the notches 7 and 8, the bolt member is raised clear of the sill socket 10. The outward pressure of the grain forces the casting 1, to swing outwards on its pivotal bearing 13, allowing the plank to be removed.

I am aware that prior to my invention grain doors have been made, wherein a plank or barrier has been adjustably restrained against the outward thrust of the grain, and released by the disengagement of mechanical parts. I therefore do not claim such a combination broadly, but—

What I claim is:

1. The combination with a doorway, of an angular casting abutting the face of the door jamb, an extension lug formed thereon engaging in a socket in the interior wall surface adjacent to the doorway, a vertical sleeve in the said casting, a bolt slidably supported in the said sleeve adapted to engage in a socket in the sill of the doorway, means for actuating the bolt to engagement or disengagement with the sill, means limiting the travel of the bolt in the sleeve, a barrier member across the doorway supported by the casting at one end and by the opposite door jamb at the other end, means preventing lateral motion of the barrier member.

2. The combination with a doorway, of an

- angular casting abutting the face of the door jamb, an extension lug formed thereon engaging in a socket in the interior wall surface adjacent to the doorway, a vertical sleeve in the said casting, ports in the said sleeve, a bolt slidably supported in the sleeve adapted to engage in a socket in the sill of the doorway, notches on the face of the bolt exposed through the ports in the sleeve, means limiting the travel of the bolt in the sleeve, a barrier member across the doorway supported by the casting at one end and by the opposite door jamb at the other end, means preventing lateral motion of the barrier member.
3. The combination with a doorway, of an angular casting abutting the face of the door jamb, an extension lug formed thereon en-

gaging in a socket in the interior wall surface adjacent to the doorway, a vertical rib 20 on the casting projecting on the interior face, a vertical sleeve in the said casting, ports in the said sleeve, a bolt slidably supported in the sleeve adapted to engage in a socket in the sill of the doorway, notches 25 on the face of the bolt exposed through the ports in the sleeve, means limiting the travel of the bolt in the sleeve, a barrier member across the doorway supported by the casting at one end and by the opposite door jamb 30 at the other end, a projecting rib formed on the exterior face of the barrier member engaging with that door jamb opposite to the casting all substantially as specified and for the purpose set forth.

JOHN JENKINS.
